Specification of Letters Patent and Drawing of Patent No. 2,609,663, dated Sept. 9, 1952, for "Rotatable Combustion Apparatus for Aligning Individual Flame Tubes with Access Parts or Manholes," filed July 21, 1951, by Philip P. Newcomb, Manchester, Conn., assignor to United Aircraft Corporation, East Hartford, Conn., a corporation of Delaware.

UNITED STATES PATENT OFFICE

2,609,663

ROTATABLE COMBUSTION APPARATUS FOR ALIGNING INDIVIDUAL FLAME TUBES WITH ACCESS PARTS OR MANHOLES

Philip P. Newcomb, Manchester, Conn., assignor to United Aircraft Corporation, East Hartford, Conn., a corporation of Delaware

Application July 21, 1951, Serial No. 237,964

12 Claims. (Cl. 60—39.31)

2

The present invention relates to gas turbine power plants and particularly to an arrangement for removal and repair or replacement of either the entire flame tube or the fuel inlets and entrance heads of the individual flame tubes of the combustor.

It has generally been necessary in removal of the burner cans to remove the surrounding casing which extends between the compressor and turbine casings and in many cases to disassemble either the straightening vane assembly in the discharge end of the compressor or the turbine nozzle assembly in order that the cans may be removed. The principal object of the present invention is an arrangement by which to provide access to the individual burner cans through a manhole provided in the casing.

If the combustor is of the so-called can-annular type in which the gas path from the compressor to the turbine is a large annulus with the burning taking place in individual cans located within the annulus, it is possible, in accordance with the invention, to remove the nozzles and inlet heads from the individual burner tubes through a single manhole by arranging them so that they may be rotated within the annular duct in which they are positioned.

Another feature of the invention is a construction of the combustor such that the flame tubes may be rotated as a unit within the annular duct in which they are positioned so that any one of the flame tubes may be selectively positioned adjacent to the opening through which the tubes may be accessible. Another feature of the invention is the arrangement of the fuel manifold for all of the burner cans in such a way that it forms a part of the rotatable structure.

Another feature is an arrangement for removal of both end caps and the associated flame tubes so that they may be inspected and repaired or replaced.

Other objects and advantages will be apparent from the specification and claims, and from the accompanying drawings which illustrate an embodiment of the invention.

Fig. 1 is a longitudinal sectional view through the combustor.

Fig. 2 is a sectional view on the line 2—2 of Fig. 1.

Fig. 3 is the burner cap assembly removed from the power plant.

Fig. 4 is a view similar to Fig. 1 showing a modification.

Fig. 5 is a sectional view substantially on the line 5—5 of Fig. 4.

With reference first to Fig. 1, the combustor construction is shown in a gas turbine power plant in which the compressor 2 discharges compressed air past straightening vanes 4 into an annular duct 6 which extends from the discharge end of the compressor to the inlet or nozzle guide vanes 8 of the turbine 10. The compressor rotor 12 is connected by a shaft 14 to the turbine rotor 16 so that both rotors turn as a unit. The shaft 14 may be supported in concentric relation to the annular duct 6 by a framework 18 which supports bearings 20 for the shaft.

The annular duct 6 has a diffuser section 22 defined by diverging walls 24 and 26, and a substantially cylindrical portion 28 defined by walls 30 and 32 both concentric to the axis of the shaft 14 and forming extensions of the walls 24 and 26. Downstream of the cylindrical portion the duct is defined by converging walls 34 and 36 forming extensions of walls 30 and 32 and extending to the turbine inlet. A surrounding casing 38 extends around the outside of the annular duct and forms a connection between the outer wall 24 of the diffuser and a forwardly projecting portion 40 of the turbine casing.

The diffuser wall 24 has an opening 42 therein which has a removable cap 44 forming a part of the diffuser wall. This cap may be held in place as by screws 46 and preferably has projecting therethrough one or more fuel supply pipes 48 which are removably connected to the fuel manifold 50 as by unions 52.

Within the annular duct 6 are a plurality of flame tubes or burner cans 54 (see also Fig. 2) which are of such a diameter that they fit within the annular duct in spaced relation to the walls thereof, being held in the desired spaced relation by clips 56. The downstream ends of the burner cans are tapered but not as rapidly as the opposite walls of the duct to engage with the walls of the duct at a point somewhat above the turbine nozzle. At the upstream end of the burner duct there is an annular closure cap 58 for the flame tube which also forms a support for the upstream end of a central tube 60 located within the burner can. This tube is supported as by vanes 62 at its downstream end. The particular arrangement of the burner cans is described in greater detail in the copending application of Axel L. Highborg, Serial No. 150,973, filed March 21, 1950.

The cap 58 has a number of angularly spaced openings 64 therein which receive cups 66, the open ends of which are attached to the caps and face in a downstream direction. The bases of

these caps receive individual fuel nozzles 68 as will hereinafter appear. The cap 58 has a peripheral flange 70 which fits within the upstream end of the burner can 54 and is spaced therefrom by a wiggle strip 72. This flange 70 also provides a pilot for the fairing member 14 for the end of the burner can.

The member 14 is in the form approximately of a cone which extends forwardly from the burner can with its walls in spaced substantially parallel relation to the diffuser portion of the annular duct. The upstream end of the member is shaped approximately to a rectangle (see Fig. 2) and has attached thereto an inner duct member 76 which functions to direct secondary air into the tube 60. It will be noted that the duct 76 is notched as at 78 to provide for the escape of primary air into the space between the member 14 and the duct 76. It may be noted that the secondary air entering the tube 60 escapes into the space surrounding the tube through openings 80 and the secondary air surrounding the can 54 also enters this space through the openings 82.

The member 14 has positioned therein the individual fuel nozzles 68 which fit within the bottoms of the cups 66. These nozzles are preferably supported by the fuel supply tubes 84 which extend between the nozzles and which are also connected to a mounting bracket 86 extending through the wall of member 14. This mounting bracket is adapted to be fastened to a support plate 88 to provide fuel communication with the tubes 90 forming a part of the fuel manifold 50. The fuel manifold is supported by a series of rollers 92 on a cylindrical part 94 of the supporting frame 18 in such a manner that, once the manhole cover 44 has been removed and the fuel pipe 48 separated from the manifold, it may be slid forward as a unit, carrying therewith the members 14 for the several burner cans and also carrying with it the individual fuel nozzles. The contours of the member 76 and the walls 24 and 26 are such that the longitudinal movement available for the members will move the downstream end of the cap 58 with the caps therein far enough forward so that it will clear the ends of the flame tubes and permit the entire fuel manifold assembly with the caps to be turned on the rollers 92 until the particular cap assembly needing repair or replacement is opposite the manhole. With the particular cap accessible it can be removed merely by undoing the screws 96 which hold the bracket 86 on the mounting plate 88. With this arrangement it is therefore possible to remove and repair or replace any one of the burner caps without the necessity for disassembling the entire engine.

Referring now to Figs. 4 and 5, the burner duct 28' which communicates between the discharge of the compressor 2' and the inlet of the turbine 10' is so arranged that the entire flame tube may be removed from the duct. In this arrangement the removable cap 44' is somewhat larger than the cap 44, being of sufficient area that the entire flame tube 54' may be withdrawn as indicated by the dotted lines in Fig. 4. The burner can 54' is supported adjacent its downstream end by a ring 100 which supports on its inner surface a series of rollers 102 engaging in a depression 104 provided in the inner wall 32 of the annular duct. The ring 100 may be split as shown to provide for assembly. The ring 100 carries supporting loops 106 75

on its outer surface in a position to be engaged by clips 108 carried by the burner tube. This clip as will be noted has axially slideable engagement with the loop so that as the burner tube is pulled forwardly the clip is disengaged and permits the entire burner tube to be withdrawn.

The front end of the inner tube is supported by spacing clips 56' as in the arrangement of Fig. 1. The burner cap 14' is mounted on the fuel manifold 50' as above described and is arranged to be withdrawn in the manner above described. It will be apparent that in this arrangement the individual flame tube with its associated cap will be placed in alignment with the manhole cover or cap 44' by turning the group of flame tubes as a unit within the annular duct. Once the flame tube and cap are in position it is obvious that they are readily removed from the duct for repair or replacement.

It is to be understood that the invention is not limited to the specific embodiment herein illustrated and described, but may be used in other ways without departure from its spirit as defined by the following claims.

I claim:

1. In a gas turbine power plant, a compressor, a turbine, an annular duct from the compressor discharge to the turbine inlet, said duct having an outer wall with an opening therein, and a number of flame tubes positioned in said duct in parallel relation to each other, in combination with a removable cover for the opening in said outer wall, and means for supporting said flame tubes for rotation as a unit within said duct to position any one of the tubes in alignment with the opening.

2. In a gas turbine power plant, a compressor, a turbine, an annular duct from the compressor discharge to the turbine inlet, said duct having an outer wall with an opening therein, and a number of flame tubes positioned in said duct in parallel relation to each other, each of said flame tubes having a cap at the inlet end in combination with a removable cover for the opening in said outer wall, means for supporting said caps for rotation as a unit within said duct to position any one of said caps in alignment with said cover for removal of said cap through the opening in said outer wall.

3. In a gas turbine power plant, a compressor, a turbine, an annular duct from the compressor discharge to the turbine inlet, said duct having an outer wall with an opening therein, and a number of flame tubes positioned in said duct in parallel relation to each other, each of said flame tubes having a cap at the inlet end in combination with a removable cover for the opening in said outer wall, and means for supporting said flame tubes and caps for rotation as a unit within said duct to position any one of the tubes and associated caps in alignment with the cover for removal of said cap and tube through the opening in said outer wall.

4. In a gas turbine power plant, a compressor, a turbine, an annular duct from the compressor discharge to the turbine inlet, said duct having an outer wall with an opening therein, and a number of flame tubes positioned in said duct in parallel relation to each other, each of said flame tubes having a cap at the inlet end, each cap supporting at least one fuel nozzle, in combination with a removable cover for the opening in said outer wall, and means for supporting

said caps for rotation as a unit within said duct to position any one of the caps in alignment with the cover for removal of the cap and nozzle through the opening.

5. In a gas turbine power plant, a compressor, a turbine, an annular duct from the compressor discharge to the turbine inlet, said duct having an outer wall with an opening therein, and a number of flame tubes positioned in said duct in parallel relation to each other, each of said flame tubes having a cap at the inlet end, each cap supporting at least one fuel nozzle, in combination with a removable cover for the opening in said outer wall, and means for supporting said caps and flame tubes for rotation as a unit within said duct to position any one of the tubes in alignment with the cover.

6. In a gas turbine power plant, a compressor, a turbine, an annular duct from the compressor discharge to the turbine inlet, said duct having an outer wall with an opening therein, a cover removably secured to said opening, flame tubes positioned in said duct in parallel relation to each other, caps at the upstream ends of the flame tubes, and fuel nozzles supported in said caps in combination with means for supporting said caps and fuel nozzles for rotation as a unit about the axis of the duct for positioning any one of the caps in alignment with the opening.

7. In a gas turbine power plant, a compressor, a turbine, an annular duct from the compressor discharge to the turbine inlet, said duct having an outer wall with an opening therein, a cover removably secured to said opening, flame tubes positioned in said duct in parallel relation to each other, caps at the upstream ends of the flame tubes, and fuel nozzles supported in said caps in combination with means for supporting said caps, fuel nozzles, and flame tubes for turning as a unit about the axis of the annular duct to position any one of the tubes and associated caps in alignment with the opening.

8. In a gas turbine power plant, a compressor, a turbine, an annular duct from the compressor discharge to the turbine inlet, said duct having an outer wall with an opening therein, a cover removably secured to said opening, flame tubes positioned in said duct in parallel relation to each other, caps at the upstream ends of the flame tubes, and fuel nozzles supported in said caps in combination with means for supporting said caps, fuel nozzles, and flame tubes for turning as a unit about the axis of the annular duct to position any one of the tubes and associated caps in alignment with the opening, said opening being large enough to provide for removal of the cap and associated flame tube from the power plant.

9. A gas turbine power plant including an annular duct in which the combustion of fuel takes place, said duct having an outer wall with an opening therein, a cover plate on said opening, a number of flame tubes positioned in said duct in parallel relation to each other, a cap at the inlet end of each flame tube, and at least one fuel nozzle supported by each cap in combination with a fuel manifold located within said duct and supported for turning therein about the axis of the duct, each of said end caps be-

ing connected to the fuel manifold, and means for sliding said manifold and the caps mounted thereon axially of the duct to remove the caps from engagement with the flame tubes such that the manifold with the caps thereon may be turned for positioning a selected cap in alignment with the opening.

10. A gas turbine power plant including an annular duct in which the combustion of fuel takes place, said duct having an outer wall with an opening therein, a cover plate on said opening, a number of flame tubes positioned in said duct in parallel relation to each other, a cap at the inlet end of each flame tube, and at least one fuel nozzle supported by each cap in combination with a fuel manifold located within said duct and supported for turning therein about the axis of the duct, each of said end caps being connected to the fuel manifold, and means for sliding said manifold and the caps mounted thereon axially of the duct to remove the caps from engagement with the flame tubes such that the manifold with the caps thereon may be turned for positioning a selected cap in alignment with the opening, each cap being piloted on the flame tube for axially sliding movement.

11. A gas turbine power plant including an annular duct in which the combustion of fuel takes place, said duct having an outer wall with an opening therein, a cover plate on said opening, a number of flame tubes positioned in said duct in parallel relation to each other, a cap at the inlet end of each flame tube, and at least one fuel nozzle supported by each cap in combination with a fuel manifold located within said duct and supported for turning therein about the axis of the duct, each of said end caps being connected to the fuel manifold, and means for sliding said manifold and the caps mounted thereon axially of the duct to remove the caps from engagement with the flame tubes such that the manifold with the caps thereon may be turned for positioning a selected cap in alignment with the opening, each cap being separable from the fuel manifold to provide for removal of the cap from the power plant.

12. A gas turbine power plant including an annular duct in which the combustion of fuel takes place, said duct having an outer wall with an opening therein, a cover plate on said opening, a number of flame tubes positioned in said duct in parallel relation to each other, a cap at the inlet end of each flame tube, and at least one fuel nozzle supported by each cap in combination with a fuel manifold located within said duct and supported for turning therein about the axis of the duct, each of said end caps being connected to the fuel manifold, and means for sliding said manifold and the caps mounted thereon axially of the duct to remove the caps from engagement with the flame tubes such that the manifold with the caps thereon may be turned for positioning a selected cap in alignment with the opening, said cover having at least one fuel inlet tube extending therethrough and connected to but separable from the fuel manifold.
